Primary Examiner — Shannon W Morgan*Assistant Examiner* — Altaira J Swangin(74) *Attorney, Agent, or Firm* — Weiss & Moy, P.C.; Jeffrey D. Moy(57) **CLAIM**

The ornamental design for a foam pad for a mattress, as shown.

DESCRIPTION

FIG. 1 is a top perspective view of a foam pad for a mattress showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
